UNITED STATES PATENT OFFICE.

JOHN HAYS HAMMOND, JR., OF GLOUCESTER, MASSACHUSETTS.

SYSTEM OF RADIO TELEGRAPHY AND TELEPHONY.

Application filed September 25, 1917. Serial No. 193,139.

To all whom it may concern:

Be it known that I, JOHN HAYS HAMMOND, Jr., a citizen of the United States, and a resident of Gloucester, in the county 5 of Essex and State of Massachusetts, have invented certain new and useful Improvements in Systems of Radio Telegraphy and Telephony, of which the following is a specification.

10 Some of the objects of this invention are to provide improved means for the transmission of radiant energy; to provide improved means for the reception of radiant energy; and to provide other improvements 15 as will appear hereinafter.

In the accompanying drawings:

Figure 1 is a diagrammatic representation of a transmission system constructed in accordance with this invention;

20 Fig. 2 is an enlarged, fragmentary, top plan view of the same;

Fig. 3 is a diagrammatic representation of a receiving system constructed in accordance with this invention; and

25 Fig. 4 is a diagrammatic representation of the waves of electro-radiant energy emitted by the transmission system shown in Fig. 1.

Referring to the drawings and particularly to Fig. 1, one form of transmission system constructed in accordance with my invention comprises an open, aerial, transmitting circuit 1, including an upright antenna 2, the lower end of which is connected to one end of an insulated impedance coil 3. The other end of the coil 3 is connected to one end of a conductor 4 which is grounded through an inductance 5 at 6. The inductance 5 forms the secondary of a step-up 30 transformer 10, the primary coil 11 of which is inserted in a closed, oscillatory circuit 12 which includes a variable condenser 13, and which is arranged to be energized by a high frequency electric alternator 15 under 35 the control of a switch 16. This alternator 15 is arranged to be rotated at any desired uniform rate to produce the desired number of alternations in the closed circuit 12. For instance, the alternator 15 may be rotated so 40 as to produce 50,000 alternations per second to cause the antenna 2 to emit radiant oscillations accordingly in a well known manner.

For modifying from time to time at the will of an operator the electro-radiant oscillations emitted by the antenna 2 as a result

of the action of the alternator 15 upon the closed circuit 12, the insulated coil 3 is arranged around one portion of an open, rectangular core 20 which may be provided with a bridge 21, and which is preferably 60 made of laminated soft iron in a well known manner. For magnetizing the core 20 from time to time at the will of an operator and intermittently in synchronism with the operation of the alternator 15, means is provided comprising a battery 25, one pole of which is connected by a conductor 26 to one end of an insulated coil 27 which surrounds a portion of the core 20. The other end of the coil 27 is connected by a conductor 28 65 and branch conductor 29 with a brush 30 which engages a commutator 31. The commutator 31 is also provided with a second brush 32 which is connected by a conductor 33 to a fixed terminal 34. The other pole 70 of the battery 25 is connected by a conductor 39 to a switch 40 which is arranged to swing about a pivot 41 into and out of engagement with the terminal 34 or with a fixed terminal 42 which is connected by a conductor 43 to 75 the conductor 28 leading from one end of the coil 27. The arrangement of the switch 40 and the fixed contacts 34 and 42 is such that when the switch 40 is in engagement with the fixed contact 34 and the commutator 31 80 is operated, a circuit is intermittently closed through the battery 25, the coil 27, and the commutator, and when the switch 40 is in engagement with the other fixed contact 42, the commutator 31 is cut out, and the circuit 85 through the battery 25 is maintained continuously closed through the coil 27 and conductor 43. When the free end of the switch 40 is spaced between the two fixed contacts 34 and 42, the circuit through the battery 25 90 and coil 27 is kept open. The parts are preferably so arranged and proportioned that when the circuit is closed through the battery 25 and the coil 27, the core 20 will 95 be magnetized up to the point of "saturation". For convenience of description, the core 20 with the parts immediately cooperating therewith may be referred to hereinafter as the wave-modifying device 45.

The commutator 31 may be constructed in 105 any suitable manner to interrupt the current from the battery 25 through the coil 27 momentarily and intermittently at any desired rate when the switch 40 is in engagement with the fixed contact 34. For in- 110

stance, as shown in Fig. 2, the commutator 31 may consist of a cylindrical body portion 50 driven by a shaft 46 connected with the alternator 15. The body portion 50, as shown, is made of insulating material and is provided with a continuous ring 51 of conducting material arranged to be engaged by the brush 30 and with an annular series of spaced, conducting segments 52 arranged 10 to be engaged successively by the brush 32, the ring 51 and the conducting segments 52 being rigidly secured to the body portion 50, and the conducting segments 52 being electrically connected to the continuous 15 conducting ring 51 by conductors 53. The spaces between the conducting segments 52 are uniform in width and of such a width that the corresponding brush 32 will momentarily break the circuit through the battery 25 each time that one segment 52 is moved 20 out of engagement with the brush 32, the next segment 52 being immediately thereafter moved into engagement with the brush 32.

25 While the commutator just described is one form of interrupter that may be used, it is to be understood that any suitable form of interrupter may be employed in the place of the above described commutator. For instance, it has been found that a rapidly revolving jet of mercury (as described by Max Levy in the Elektrotechnische Zeitschrift of October 12, 1899, Vol. 20, page 717) can be used as a high frequency interrupter for electrical currents, or any other suitable form of interrupter may be so applied.

30 In the operation of the transmission system shown in Fig. 1, with the switch 16 closed, the switch 40 closed upon the fixed contact 42, and the alternator 15 in operation at a rate, for instance, of 50,000 alternations per second, corresponding oscillations will be set up in a well known manner 35 in the closed, oscillatory circuit 12 which will induce corresponding oscillations in the open, aerial circuit 1 and will thereby cause the antenna 2 to emit corresponding, sinusoidal, electro-radiant oscillations substantially in the form shown by the full curved line 75 of Fig. 4, this curved line 75 being plotted upon the straight line 76 indicating zero potential.

35 As long as the switch 40 remains in engagement with the fixed contact 42, and the core 20 is consequently magnetized up to its point of saturation, the core 20 will have practically very slight if any damping or other effect upon the radiant oscillations 40 emitted by the antenna 2; but when the circuit is broken through the battery 25 and the coil 27, thus permitting a demagnetization of the core 20, the permeability of the core to the magnetic field produced by the 45 alternations in the impedance coil 3 will be

thus rapidly and largely increased, and this magnetic field will react upon the coil 3 in a well known manner to suddenly dampen, choke or reduce the amplitude of the alternations in the coil 3 and antenna 2. Consequently, the amplitude of the electro-radiant oscillations emitted by the antenna 2 will be reduced. When the switch 40 is in engagement with the fixed contact 34, thus closing the circuit from the battery 25 through the 50 coil 27 and commutator 31, the damping effect upon the amplitude of the electro-radiant oscillations emitted by the antenna 2 will occur periodically at a rate predetermined by the construction and arrangement 55 of the commutator 31 or other interrupter, which are preferably such that the circuit through the battery 25 and coil 27 is momentarily opened at each peak of the electric alternations or oscillations in the open, 60 aerial circuit 1. Consequently, the commutator 31 produces an intermittent damping or reduction in amplitude of the electro-radiant oscillations radiated by the antenna 2, such damping occurring at each peak of 65 the oscillations radiated as indicated by the curved, broken lines 78 of Fig. 4.

It is evident from a consideration of the wave form shown in Fig. 4 that, when the wave-modifying device 45 is operating 70 through the action of its commutator 31, there exists in the antenna 1 of Fig. 1 what may be considered as a double frequency phenomenon. It is evident that there is a sinusoidal, periodic alternation of the 75 current produced in the radiating system by the alternator 15 of Fig. 1. This periodic, alternating current of approximately sinusoidal form is represented by the graph 80 75. The frequency of this alternation, as hereinbefore mentioned, is, in this particular case, 50,000 cycles per second. There is also produced in the sinusoidal wave form of the radiating current an amplitude variation effect producing a depression 78 at 85 each peak of the alternating current represented by the graph 75. There therefore exists an amplitude variation in the radiating system of approximately double the frequency of the fundamental frequency induced therein by the high frequency alternator. The arrangement is such that although the amplitude variation effect 78 occurs only twice in the cycle at the transmitting station, the variations in the receiving 90 circuit, which will follow the dotted line of Fig. 4 rectified, will comprise uni-directional pulsations at the rate of 150,000 per second.

One form of receiving system constructed 95 in accordance with this invention is shown in Fig. 3, and comprises an aperiodic or untuned receiving antenna 100 coupled through the primary winding 101 of a high-frequency oscillating transformer 103 to the 100

secondary winding 104 of the said oscillating transformer. The inductive winding 104 comprises part of an oscillatory circuit 105 containing a suitable variable condenser 106. The said oscillatory circuit 105 is aperiodic so as to respond to the coexisting frequencies emitted by the sending station of Figure 1 and is arranged to control any suitable detector, for instance, a detector 107 of the gaseous or electronic type comprising a bulb 108 containing a vacuous space and having therein a grid 109, a cathode 110 and an anode 111. The manner of operation of said detector is well known in the art. The detector 107 controls a circuit 115 containing a battery 113 and an inductance 114. It is understood that the current from the battery 113 normally flows through the detector 107 through the action of the electronic discharge from the filament 110 which is heated by a battery 112. With the variation of potential induced on the grid 109 through the alternating currents present in the oscillatory circuit 105, the current from battery 113 flowing through the detector 107 is alternately increased and decreased in specific phase relation to the alternating current present in circuit 105 which induces specific potentials in grid 109. Thus if the detector 107 be highly evacuated it will possess but little hysteresis effect and will allow in its valve action upon the current of battery 113 a modification of said battery current simulating closely the modifications taking place in the alternating current in oscillatory circuit 105. The detector 107 may, therefore, be considered as a repeating device.

Now referring to Fig. 4, it is seen that there are two coexistent frequencies in the wave form as shown. Moreover, inasmuch as the detector 107 is essentially a repeating device and an amplifying device, it will be understood that the current from the battery 113 passing through the inductance 114 and through the detector 107 will approximate closely in its amplitude variation the wave form shown in Fig. 4; that is to say, there will coexist in the circuit 115 the wave form 75 shown in full lines in Fig. 4 and another wave form of triple frequency due to the wave form 75 having been modified as indicated by the broken lines 78. Coupled to the oscillatory circuit 115 by a transformer having the inductance 114 as its primary winding and a secondary winding 116 is an oscillatory circuit 118. Said oscillatory circuit 118 comprises a variable condenser 117 and controls in a well known manner a detector 119 of any suitable form but preferably of the gaseous or electronic type.

The oscillatory circuit 118 is tuned to approximately triple the frequency of the alternator 15. The alternating currents produced in the oscillatory circuit 118 create

periodic rises of potential on the grid 120 of the gaseous detector 119 and therefore modify the current of battery 121 flowing through detector 119 through the electronic discharge from cathode 122 heated by battery 123 to the anode 124. In the circuit 125 containing the battery 121 and the telephone 126 and the circuit breaker 127, there would normally exist unidirectional pulses of current having a frequency of 150,000 per second. On account of the inertia of the diaphragms of the said telephone 126, no sound would be produced by the pulsations of current in said circuit 125 unless the circuit-breaking mechanism 127 were caused to function. Said circuit-breaking mechanism 127 may resemble any suitable form of circuit breaker as shown by me in Fig. 2, with the difference that the rate of interruption of the current in this instance is much lower. For example, it may be 1,000 breaks per second. Thus the unidirectional pulsations of current of 150,000 per second frequency in traversing the circuit 125 and the circuit-breaking mechanism 127 are broken into groups of 1,000 per second. These groups passing through the telephone 126 give rise to a high pitched note clearly distinguishable by the human ear from atmospheric electricity and other sources of interference.

Instead of reducing the pulsating current of 150,000 per second to audible frequency by means of the break mechanism 127, it is possible to produce the same effect by other means well known in the art. For instance, if the break mechanism 127 be closed, apparatus may be employed for this purpose comprising an oscillatory circuit 129 inductively coupled by a suitable transformer 128 to the oscillatory circuit 118 and energized by a suitable high frequency alternator 130 at the rate of 151,000 alternations per second, or other suitable number of alternations. If the frequency of the high frequency alternator 130 be at the rate of 151,000 alternations per second, periodic amplitude variations or beats of electrical current of a frequency of 1,000 per second will be produced in the oscillatory circuit 118. Thus in circuit 125, there would be produced pulsations of current at the rate of 1,000 per second which would produce in the telephones 126 the desired high pitched note. In the use of a separate alternating current circuit coupled to the oscillatory circuit 118, I employ the well known heterodyne receiving method. By having the detector 119 oscillate as an autodyne or source of continuous oscillations by methods well known in the art, the same effects could be produced and the same beat reception obtained.

In the use of the system for telegraphy, the transmitted energy may be modulated in accordance with signals by manipulation of

the switch 16 or of a second switch or key which those skilled in the art will have no difficulty in providing in the arrangement shown in Fig. 1 in a usual or suitable manner. Likewise, if it is desired to employ the invention in telephony, those skilled in the art can readily provide a telephone transmitter in proper relation to the other parts of the transmitting arrangement shown in

10 Fig. 1.

One of the advantages of this invention is that it provides in the receiving system a double selectivity from extraneous interference through the conjoint action of two receiving circuits having widely different periodicities but operating successively to register signals. Thus any interfering waves having a periodicity sufficiently close to the first receiving circuit to force the same into 20 oscillations would be unable to force the second circuit whose periodicity varies greatly from that of the interfering wave.

Another advantage obtained is the advantage of secrecy of transmission of messages. 25 The ordinary system now in use is only capable of receiving the wave form represented by graph 75 in Fig. 4, whereas my system is only responsive to the modified wave form as shown in graph 78 of Fig. 4. Thus, by 30 the employment of this improved system of wave transmission and reception, it is possible to secure secrecy and immunity from interference from the present type of radio-transmission systems.

35 While I have shown specifically a ratio of frequencies in the wave forms shown in Fig. 4 of 1 to 3, it is obvious that the ratio may be varied by variation of the speed or construction of the commutator 31 of Fig. 2 and 40 by correspondingly changing the tuning of the circuits of the receiving system.

It is to be understood that this invention is not limited to the specific system herein disclosed, but might be embodied in various 45 systems without departing from the spirit of the invention or the scope of the appended claims.

Having thus fully described my invention, I claim:

50 1. In a system for the transmission of energy, the combination with means for producing a series of electric oscillations, of means operative during a predetermined portion of each half cycle of each oscillation only to vary the amplitude of each of said oscillations in a uniform manner.

55 2. In a system for the transmission of energy, the combination with means for generating a series of electrical oscillations, of means operative during a predetermined portion of each half cycle of each oscillation only to impress upon each of said oscillations a plurality of intermittent amplitude variations.

60 3. In a system for the transmission of en-

ergy, the combination with means for producing a series of electric oscillations, of means operative to momentarily vary the amplitude of each of said oscillations in a uniform manner and means for receiving said oscillations and variations including cooperating elements tuned to the frequency of said oscillations and the frequency of said variations respectively.

65 4. In a system for the transmission of energy, the combination with means for generating a series of electrical oscillations, of means operative to impress upon each of said oscillations a plurality of intermittent amplitude variations, and means for selectively receiving said oscillations and said variations including cooperating elements tuned respectively to the frequency of said oscillations and the frequency of said variations.

70 5. In a system of radio transmission, the combination with means for generating a series of electro-radiant oscillations having a predetermined frequency, of means for periodically varying the amplitude of said oscillations respectively, the amplitude of each oscillation being varied only during a 75 total amount of time appreciably less than the total duration of said oscillation.

75 6. In a system of radio transmission, the combination with means for generating a series of electro-radiant oscillations having a predetermined frequency, of means for repeatedly modifying the amplitude of each of said oscillations at a predetermined frequency greater than said first-mentioned frequency, and means for receiving said oscillations and said variations including cooperating elements tuned respectively to said frequencies.

80 7. In a system for the transmission of radiant energy, the combination with means for transmitting a series of electro-radiant oscillations normally having a sinusoidal form, of means operative to vary the form of each of said oscillations during only a portion of each half cycle of each oscillation.

85 8. In a system for the transmission of radiant energy, the combination with means for transmitting a series of electro-radiant oscillations normally having a sinusoidal form, of means operative to vary the form of each of said oscillations, and means for receiving said oscillations and variations including cooperating elements tuned respectively to the frequency of said oscillations and to the frequency of said variations.

90 9. In a system for the transmission of radiant energy, the combination with an aerial circuit including a coil, of means operative to cause said circuit to emit electroradiant oscillations, and means for periodically varying the amplitude of said oscillations including an electro-magnetic core arranged

to control said coil, and means synchronized with said first mentioned means for intermittently magnetizing said core.

10. In a system for the transmission of 5 radiant energy, the combination with an aerial circuit including a coil, of means operative to cause said circuit to emit electro-radiant oscillations, and means for periodically varying the amplitude of said oscillations including an electro-magnetic core arranged to vary the impedance of said coil, and means synchronized with said first mentioned means for intermittently magnetizing said core.
15. 11. A system for the transmission of electric energy comprising a circuit, means for producing electric oscillations in said circuit, and means automatically operative to vary the amplitude of each half-cycle of said oscillations during a time less than the time period of the respective half-cycle.

20. 12. The method for the transmission of electric energy which consists in producing a series of electro-radiant impulses, producing 25 in said impulses a series of periodic variations having a frequency not less than the frequency of said impulses, and receiving said impulses and variations upon two cooperating elements tuned to the frequency 30 of said impulses and the frequency of said variations, respectively.

35. 13. The method of transmitting electric energy which consists in generating periodic electric impulses producing in said impulses a series of periodic variations having a frequency not less than the frequency of said impulses, selectively receiving said impulses and variations, and causing the operation of a receiving device as 40 a result of a conjoint action of said impulses and variations.

45. 14. A system for transmitting electric energy comprising means for producing periodic electrical impulses, means for producing in said impulses a series of periodic variations having a frequency not less than the frequency of said impulses, and means for receiving said impulses and variations comprising two cooperating elements tuned 50 to respond to said impulses and said variations, respectively.

55. 15. In a system for the transmission of energy the combination with a circuit including a coil, of means operative to produce electrical oscillations in said circuit, and means for varying the amplitude of said oscillations periodically including a magnetizable core arranged within the influence of said coil and means automatically operative in synchronism with said oscillations to magnetize said core during predetermined portions of said oscillations.

60. 65. 16. In a system for producing oscillations the combination with a circuit including a coil, of means operative to produce elec-

trical oscillations in said circuit and means automatically operative to vary said oscillations periodically including a magnetizable core surrounded by said coil, and means for intermittently magnetizing said core including a circuit arranged to influence said core and means for energizing said circuit in synchronism with said oscillations during predetermined portions thereof only.

17. A signaling system comprising a transmitting circuit, a saturable core, means including an alternator for producing pulsations in said circuit, and means actuated in synchronism with said alternator for causing saturation of the core to impress amplitude variations upon said pulsations.

18. A signaling system comprising a transmitting circuit, a saturable core, means for producing periodic waves in said circuit, and means actuated in synchronism with said producing means for intermittently causing saturation of the core to impress amplitude variations on said waves.

19. A radio system comprising a transmitting circuit, a saturable core, means including an alternator for producing periodic waves in said circuit, and means actuated in synchronism with said alternator for causing saturation of the core to impress amplitude variations on each of said waves.

20. A signaling system comprising a transmitting circuit, a saturable core, means including a source of electrical oscillations for producing periodic waves in said circuit, and means actuated in synchronism with said source for causing saturation of the core to impress amplitude variations on each half cycle of each of the oscillations.

21. A signaling system comprising a transmitting circuit, a saturable core, means including an alternator for producing periodic waves in said circuit, and means actuated in synchronism with said alternator for causing saturation of the core to impress during predetermined portions of said waves variations in amplitude.

22. In a signaling system the combination with a source of high frequency electrical oscillations; of a saturable core having a winding arranged to vary the amplitude of the oscillations, and means for causing said core to be saturated during predetermined portions of the oscillations.

23. In a transmitting circuit for a radio system, the combination with a source of electrical oscillations; of a saturable core having a winding arranged to vary the amplitude of the oscillations, and means for saturating said core in synchronism with the active periods of said source and effective only during predetermined portions of the periods.

24. A method of signaling which consists in generating a series of waves of a predetermined frequency having impressed there-

in a series of variations of a higher frequency, and selectively receiving the energy of said waves and variations upon co-operating receiving elements, one of which is responsive to the combined energy of said waves and variations, and the other of which is responsive only to said variations.

25. A method of signalling which consists in generating a series of waves of a predetermined frequency having impressed there-in a series of variations in amplitude of a higher frequency, and selectively receiving the energy of said waves and variations in amplitude upon cooperating receiving elements, one of which is responsive to the combined energy of said waves and variations in amplitude, and the other of which is responsive only to said variations in amplitude.

20 26. A signalling system comprising a circuit, means for producing electrical oscillations in the circuit, and means for producing in said oscillations a frequency component of a harmonic of the fundamental frequency of the oscillations, said means comprising a core of magnetic material having a winding connected in said circuit, a second circuit including a source of direct current, a winding operatively connected with the magnetic core and means for interrupting the flow of direct current in the last-mentioned circuit, and means for operating the interrupting means in synchronism with the

means for producing the electrical oscillations.

27. A signalling system comprising a circuit, means for producing electrical oscillations in the circuit and means for producing in said oscillations a component of a frequency equal to three times the fundamental frequency of the oscillations, said means comprising a core of magnetic material, a winding in said circuit under the influence of the core, a second circuit including a source of direct current, a winding operatively connected with the magnetic core and means for interrupting the flow of direct current in the last-mentioned circuit, and means for operating said interrupter in synchronism with the means for producing the electrical oscillations to magnetize the core at periods corresponding with the peaks of the oscillations.

28. A method of wireless signalling which includes the steps of producing electrical oscillations, transmitting energy derived from said oscillations and having a fundamental frequency component and a frequency component equal to a harmonic of the fundamental frequency, modulating the transmitted energy in accordance with signals, and utilizing both of said frequency components in receiving the transmitted energy.
